UNITED STATES PATENT OFFICE.

GEORGE STANFORD WITHAM, JR., OF HUDSON FALLS, NEW YORK.

BEATING ENGINE.

Application filed December 13, 1926. Serial No. 154,508.

My invention relates to paper making and particularly to an improved device for breaking up and hydrating the stock preparatory to forming a web therefrom.

The present type of beating engine comprises an elongated, comparatively shallow, open tank having semi-cylindrical ends, and provided with a centrally disposed partition, called a midfeather. This partition terminates somewhat short of the ends of the tank so that stock may be circulated horizontally about it.

On one side of the midfeather is the beater roll having a diameter of about twice the depth of the tank, and long enough to extend between the midfeather and the side of the tank so that any substantial flow of stock past the ends of the roll is prevented. The cylindrical surface of the roll is provided with plates and knives which coact with a bed plate beneath to cut, comb, draw out or break up the pulp into its elemental fibers.

In the present type of machine, a comparatively high, dam-like wall, called a backfall, is provided behind the roll. This wall extends from the bottom of the tank upwardly to about the middle of the roll, or quite close to the top of the tank. The movement of the roll reduces the normal, static depth of the stock in front of the roll by drawing stock from this part of the tank, passing it between the roll and bed plate and projecting it over the top of the backfall into the tank at the rear of the roll where the normal static depth of stock is increased. In this way a considerable difference in depth or head is established which creates a gravitational flow of stock from the rear to the front of the roll. On account of the backfall, very little circulation is caused by the direct, impelling action of the roll, and the rate is almost wholly dependent upon the consistency of the stock and the head or difference in depth of the stock stream at the backfall and at the front of the roll. The consistency of the stock cannot be increased to the point where it will not flow sufficiently fast to feed the roll at the front, and under actual working conditions the head which can be established is otherwise materially limited by the fact that some appreciable depth of stock must be maintained immediately in front of the roll. The present practice is to have the degree of concentration such that the difference in elevation between the surface of the sluggishly moving stock stream at the rear of the roll and the

surface at the end of the stream just in front of the roll is considerable. In other words, the tank is substantially full of stock at the backfall where the utilization of its capacity is about 100%, but in front of the roll, the level of the stock stream is far below the top of the tank and the percentage capacity utilization between the backfall and the front of the roll decreases about uniformly, and the average percentage probably does not exceed 65%.

The efficiency of a beating engine may be very greatly increased by increasing the degree of concentration of the stock and increasing its rate of circulation. The hydration of the stock may be improved, and hence the efficiency of the engine increased, by maintaining a greater depth of stock in front of the roll than is now possible, thus avoiding the whipping of air into the stock which interferes with the hydration thereof. Furthermore, the charge capacity of the present type of machines may be very greatly increased without increasing the floor space occupied, by providing means whereby the stock may be circulated at a greatly increased depth throughout substantially the whole machine.

The objects of my invention, therefore, are to provide—

1st. A beating engine in which a stock mass having a higher degree of concentration than heretofore may be circulated.

2nd. A machine which will circulate a highly concentrated stock more rapidly than is possible with the present types.

3rd. A machine occupying substantially the same floor space as the present type but capable of containing and operating upon a greatly increased volume of stock.

4th. A machine in which a greater depth of stock may be maintained in front of the roll to avoid the whipping of air into the stock, thereby completely filling that section between the beater bars and attaining full efficiency as the stock passes between the roll and the bed plate.

I propose to accomplish these objects by forcing the stock mass away from the rear of the beater roll by means of a screw propeller and driving it under pressure, so to speak, towards the front of the roll where the pressure is relieved and the comparatively thick mass flows downwardly toward the beater roll partly by gravity and partly by the driving force of the stock behind. By

forcing the stock about in the beater and thus reducing the length of the gravitational flow, I am able to use a more highly concentrated stock, to maintain the surface of the stock at

5 a high elevation throughout the machine, thereby utilizing its full capacity, and to circulate this highly concentrated stock mass more rapidly than it is possible to circulate a diluted stock in the present type of machine.

10 Referring to the accompanying drawings—

Fig. 1 is a plan view of my beating engine with a portion of the cover broken away

Fig. 2 is a section of Fig. 1 in the broken planes 2—2;

15 Fig. 3 is a section of Fig. 1 in the plane 3—3;

Fig. 4 is a section of Fig. 1 in the plane 4—4; and

20 Fig. 5 is a typical, developed profile of the stock stream from the backfall to the front of the roll at about one-half the scale of the other figures.

In the drawings, 1 represents the floor or foundation upon which the tank, 2, is erected.

25 The tank is provided with the cylindrical ends, 3, and the central partition or midfeather, 4. Between one side of the tank and the midfeather is the beater roll, 5, mounted upon the spindle or shaft, 6, and provided

30 with suitable bearings not shown. Upon the bottom of the tank, below the roll, is the bed plate, 7. The usual guard or cover, 8, is provided over the roll, but instead of leaving the tank otherwise open at the top, as has been

35 usual, I provide covers, 9, extending from the roll guard, 8, about the end of the tank behind the roll, and preferably, to about the center of the opposite end. The portion, 10, of the tank immediately in front of the roll is left open so that the stock, size, chemicals and color may be fed into the machine, and further that stock can be taken out from time to time for test purposes.

40 Behind the roll, I provide the propeller, 11, which is mounted upon shaft, 12, driven by motor, 13, through suitable reduction gearing, 14. The shaft, 12, is supported by the bearing, 15, within the tank, and by a suitable bearing and packing gland, 16, where it passes

45 through the end of the tank.

50 In order that the propeller may operate efficiently, the cover plates, 9, are semi-cylindrical in form and the angles formed between the sides and bottom of the tank are filleted or built up as shown at, 17, so that, about the periphery of the propeller, and preferably throughout the covered portion of the tank behind the propeller, the tank is substantially circular in section and but slightly larger than the propeller.

55 At the roll, the transverse, half section of the tank is rectangular in form, and this section is gradually changed to a circular section in the plane of the propeller by the transition surfaces 18. From the front of the bed plate

to the covered portion of the tank, the transverse half section is gradually changed from rectangular to circular by the transition surfaces, 19.

60 In the usual form of beating engine, a backfall, 20', extends upwardly around the rear portion of the roll to about the center thereof, but where a propeller is used for drawing the stock away from the roll, the backfall may be eliminated altogether or be reduced to about 75 the form shown at 20 in Fig. 1, so that the impelling action of the roll upon the stock is utilized to the fullest extent.

70 The usual doctor, 21, consisting of a heavy board with a cast iron edge just clearing the roll, may be provided to prevent stock being carried around the roll, but it is not a necessary feature in this improved type of beater.

75 As previously pointed out, the surface level of the stock in the open form of beating engine, which depends essentially upon gravity as a circulating force, is considerably higher behind the roll than it is in front of the roll. For this reason, while the tank is substantially

80 filled behind the roll it is only partially filled in front, and thus, a great deal of space within the tank is not utilized. Furthermore, in the old form of tank, the useful depth cannot

85 greatly exceed about one-half the diameter of the roll. In my closed form of engine, the depth of the tank is increased to about the diameter of the roll and practically the entire volume is utilized. This great increase in

90 volumetric capacity is diagrammatically illustrated in Figure 5 which is a small scale, 95 developed profile of the stock stream. Referring to this figure, the heavy line 22, represents the elevation of the bottom of the tank, and the inclined dotted line, 23, represents the

100 inclined surface of the stock stream in the present type of beater as it flows from the backfall around to the front of the roll. The dotted line, 24, represents the approximate, 105 relative elevation of the surface of the stock stream in my improved type of beater and shows that the depth is practically doubled

110 throughout the machine. Where the cross sectional shape of the enclosed stock passage is cylindrical, as illustrated, the sectioned portion, 25, of Fig. 5 does not precisely indicate

115 the relative increase in volumetric capacity although it does correctly represent the relative increase in depth. However, it is to be understood that my engine is not limited to a

120 cylindrical stock passage although such a form is preferred about the propeller, and where the major portion of the passage is rectangular, as in the old type, the sectioned area, 25, approximately represents the increased volumetric capacity.

125 By providing a driving means for the stock it is possible not only to increase the concentration but also to increase the rate of circulation so that with the increased volumetric capacity, it is possible to prepare

130

nearly three times the quantity of stock in one-half to three-fourths the time formerly necessary. In other words, with my improved beating engine the circulation rate is increased from 200% to 300%; the capacity, due to increased concentration and volume, is increased about 250% by weight; and the time required to prepare this charge is only 50% to 75% of the time required to prepare a charge in the present type of engine. This greatly increased efficiency is not wholly attributable to increased concentration, increased rate of circulation, and increased volumetric capacity, but is partly attributable to improved hydration of the stock as it passes under the roll. In the present type of engine with the stock riding low at the point where it is fed under the roll, a large volume of air is unavoidably carried in with the stock, thus preventing complete hydration. In my improved type, the increased depth of stock in front of the roll completely fills the section between the beater bars, thereby eliminating or greatly reducing the volume of air that is "whipped" into the stock and results in a complete hydration.

If desired, a second propeller, 11', may be provided, supported by bearings, 15' and 16', and having a driving shaft, 12', reduction gearing, 14', and a motor, 13', all similar to like numbered elements associated with the propeller, 11.

While I have illustrated and described but one form of my invention, it is to be understood that the illustrations are merely typical, that the words which I have used in describing this form are words of description rather than words of limitation, and that changes within the purview of the appended claims may be made without departing from the true scope and spirit of my invention in its broadest aspects.

What I claim is—

1. In a beating engine, the combination with a roll, of means forming an enclosed, substantially horizontal stock passage from the rear of the roll around to a point near the front thereof, and means within said passage for forcing the stock therethrough.

2. In a beating engine, the combination with a roll, of means forming an enclosed stock passage from the rear of the roll around to a point near the front thereof, and a screw propeller adapted to revolve in said passage for forcing the stock therethrough.

3. In a beating engine, the combination with a roll and tank, of means forming an enclosed, substantially horizontal stock passage from the rear of the roll throughout a substantial portion of the length of said tank, and a plurality of screw propellers adapted to revolve in said passage for withdrawing the stock from behind said roll and forcing it through said passage.

4. In a beating engine, the combination

with a roll, of means forming a closed, substantially cylindrical stock passage from a point near the rear of said roll around to a point near the front thereof, and means for driving the stock through said passage. 70

5. In a beating engine of the horizontal circulating type, the combination with a roll of a comparatively low back fall whereby stock is impelled directly from the lower portion of the roll, and means for preventing an 75 accumulation of stock directly behind the roll.

6. In a beating engine, the combination with a roll, of means forming an enclosed stock passage of a depth substantially greater than the radius of the roll and adapted to 80 convey stock horizontally from the rear of the roll to a point near the front thereof, and a propeller within said passage in proximity to the rear of the roll for circulating stock under moderate pressure in said passage. 85

7. A beating engine comprising a roll, a tank providing a passage through which the stock is circulated horizontally from the rear to the front of the roll, a cover for said tank extending rearwardly from said roll and enclosing a major portion of said passage, and a screw propeller within said enclosed portion of the passage for driving the stock therethrough. 90

8. A beating engine of the horizontal circulating type comprising means forming a continuous, stock-circulating passage, a roll, and means independent of the roll for forcing a circulation of comparatively concentrated stock in said passage; the stock circulating passage being enclosed and adapted to carry the stock under moderate pressure throughout a substantial portion thereof, but being open and of increased cross sectional area at the front of the roll; whereby the level of the stock stream adjacent the roll is materially lowered. 95

9. In a beating engine of the horizontal circulating type, a roll, means forming an enclosed, stock-circulating passage of a width 110 and depth approximating the length and diameter, respectively, of the roll and extending from the rear of the roll around to a point near the front thereof, and means independent of the roll for forcibly circulating the stock 115 in said passage.

10. In a beating engine of the horizontal circulating type, the combination with a roll, of a tub having a cross section thereof nearer the rear than the front of the roll forming 120 a substantially circular stock passage, and a screw propeller adapted to revolve in said passage for forcing the stock therethrough.

11. In a beating engine of the horizontal circulating type, the combination with a roll, of a tub providing a passage through which the stock is circulated from the rear to the front of the roll, said passage having a restriction therein comparatively near the rear 125 of the roll, and a screw propeller adapted to

revolve in said restriction for withdrawing the stock from the rear of the roll and forcing it towards the front thereof.

12. In a beating engine of the horizontal circulating type, the combination with a roll, of a tub providing a passage through which the stock is circulated from the rear to the

front of the roll, a portion of the passage nearer the rear of the roll than the front thereof being circular in transverse cross section and of restricted area, and a screw propeller mounted to revolve in said restriction for forcing the stock therethrough. 10
